MATHIAS J. WEBER, OF CHICAGO, ILLINOIS, ASSIGNOR TO HEALTH-O-METER COMPANY, OF CHICAGO, ILLINOIS, A CORPORATION OF ILLINOIS

DESIGN FOR A SCALE CASING

Application filed December 20, 1928. Serial No. 29,350. Term of patent 14 years.

To all whom it may concern:

Be it known that I, MATHIAS J. WEBER, a citizen of the United States, residing at Chicago, Cook County, Illinois, have invented a new, original, and ornamental Design for a Scale Casing, of which the following is a specification, reference being had to the accompanying drawings, forming part thereof, showing my new design.

Figure 1 is a perspective view of the scale casing, showing my new design;

Figure 2 is a side view of the same;

Figure 3 is an end view of the same; and

Figure 4 is a plan view.

I claim:

The ornamental design for a scale casing as shown.

MATHIAS J. WEBER.
